UNITED STATES PATENT OFFICE.

LYMAN C. HUFF, OF CHICAGO, ILLINOIS, ASSIGNOR TO UNIVERSAL OIL PRODUCTS COMPANY, OF CHICAGO, ILLINOIS, A CORPORATION OF SOUTH DAKOTA.

APPARATUS FOR TREATING OIL.

Application filed April 14, 1923. Serial No. 632,019.

To all whom it may concern:

Be it known that I, LYMAN C. HUFF, a citizen of the United States, and resident of the city of Chicago, county of Cook, and State of Illinois, have invented certain new and useful Improvements in Apparatus for Treating Oil, of which the following is a specification.

This invention relates to improvements in an apparatus for treating oil and refers more particularly to that portion of the apparatus utilized for recycling reflux condensate.

Among the objects of the invention are to provide an apparatus by means of which oil may be returned from the dephlegmating stage to the heating stage either through a pump or by-pass in which is positioned a valve which permits the pump to be eliminated from the system.

The single figure is a diagrammatic side elevational view of the apparatus.

Referring to the drawing, the oil to be treated is introduced from any convenient extraneous source through the line 1 and is charged into the top of the dephlegmator 2 where it is utilized as a refluxing medium traveling in an opposed direction to the hot vapors which rise through the dephlegmating column and separating out the high boiling point fractions as reflux condensate. Besides taking the form of a refluxing medium, the introduction to the dephlegmating column provides a means for preheating the oil.

The oil with what condensate it may collect in the dephlegmating column flows down through the dephlegmator leg 3 and is drawn off through the line 4 which is regulated by a valve 5. The line 4 terminates in a T connection, one arm of which is connected to a pipe 5 which introduces liquid to the suction side of the pump 6. The other arm of the T has connected thereto a pipe 7 in which is interposed a check valve 8. The opposite end of this line 7 communicates with the line 9 which is connected to the discharge side of the pump 6 and has interposed therein a valve 10 for controlling the flow of the liquid therethrough. The pump may be either of the rotary or reciprocating type, being driven by a power means diagrammatically shown at 11.

The line 9 is connected to the heating coil 12 which is mounted in a furnace 13, prefer-

ably heated by gas burners shown at 14. The oil after passing through the heating coils has been raised to a conversion temperature subsequently being discharged through the transfer line 14 regulated by a valve 15 to the expansion chamber 16.

In the expansion chamber the oil is collected in a considerable body where it is vaporized, the vapors passing off through the line 17 regulated by a valve 18, while the unvaporized, residual products may be drawn off from any of the residuum draw-off lines 19 controlled by valves 20 which are tapped into the expansion chamber at different heights. Tricocks 21 are positioned at different levels on the expansion chamber in order to ascertain the height of the liquid therein. The upper and lower ends of the expansion chamber are removable in order to facilitate cleaning.

The evolved vapors passing over from the expansion chamber rise through the dephlegmating column where they are subjected to the cooling or refluxing action of the raw oil, after which the still vaporized portions pass off through the line 22 to a water condenser 23 and are finally collected as liquid distillate in the receiving tank 24. The receiving tank is equipped with a pressure gauge 25, liquid level gauge 26, a pressure relief valve 27 and a liquid draw-off valve 28 interposed in the draw-off line 29.

By means of the relief valve 27 a regulated pressure of the generated vapors may be imposed upon the system while the valves 90 interposed in the connecting lines between the different stages furnish a means for maintaining differential pressures on the separate portions of the apparatus.

By interposing a pump 6 in the return line between the dephlegmating and heating stages a positive recirculation of the reflux condensate may be maintained. This pump obviates the necessity of relying upon a head of liquid in the dephlegmating column, 100 which circulation is at times insufficient to produce the desired velocity of the oil through the heating tube. At the same time this pump is not totally relied upon, as a by-pass line 7 is furnished by means of 105 which the pump may be cut out of the system and the reflux condensate recycled due to the head maintained in the refluxing column. By installing a check valve in the by-pass line in case of failure of the pump 110

for any reason, this oil line would be automatically opened and deliver the oil to the heating tubes. In normal operation while the pump is working the check valve 8 will be closed due to the differential pressures between the suction and discharge sides of the pump. Thus the check valve provides an automatic means of recirculating the oil through the tubes in case the positive means or circulating pump fails. This circulation through the by-pass line would depend wholly upon the gravity head of liquid building up in the reflux leg.

In case of failure of the pump it may be wholly eliminated from the system by closing off the valves 10 in the line 9 and the valve 30 in the line 5, resulting in the oil passing entirely through the by-pass line 7 to the heat coil.

In addition to the recycling of the reflux condensate, the mixture of reflux condensate and raw oil will be charged to the heating tubes in the manner explained.

I claim as my invention:

1. In an apparatus for treating oil, the combination with a heating coil through which a stream of oil is passed to be heated to a cracking temperature, an enlarged conversion chamber receiving said highly heated oil and in which chamber a substantial portion thereof vaporizes, of a dephlegmating means connected to the conversion chamber, a recycling line for returning the reflux condensate to the heating means for retreatment, a pump interposed in said line, a by-pass around the pump and a check valve in said by-pass whereby the recirculation continues automatically with the failure of the pump by head pressure.

2. In an apparatus for treating oil, the combination with a furnace, a heating coil therein, an enlarged expansion chamber, means for transferring the highly heated oil from said heating coil to said chamber where conversion of the oil occurs, a dephlegmator, means for passing vapor from said chamber to said dephlegmator, a reflux collecting line extending from said dephlegmator in which a body of reflux oil accumulates, means for recycling said reflux condensate through said heating coil comprising a recycling line, a pump interposed in said line, and a by-pass around said pump, and an automatically acting valve in said by-pass for feeding reflux oil by head pressure to said heating coil in the event said pump becomes inactive.

3. In an apparatus for treating oil, the combination with a heating coil, of a furnace in which said coil is disposed, an enlarged conversion chamber adjacent said coil, means for transferring heated oil from the coil to said conversion chamber, a dephlegmator, means for discharging vapors generated from said oil to said dephlegmator, a reflux receiver disposed below said dephlegmator in which reflux oil accumulates, a feeding line leading from said receiver to said heating coil, a pump disposed in said line, a by-pass extending around said pump, and means in said by-pass for preventing the passage of reflux oil therethrough when said pump is operating, said means acting automatically to permit reflux oil to pass around said pump through said by-pass when said pump is inactive.

LYMAN C. HUFF.
